I Inventor,
Allan L. McGregor,
By Officed, Worcester, Mass.

UNITED STATES PATENT OFFICE.

ALLAN L. McGREGOR, OF CHICAGO, ILLINOIS.

DESIGN FOR A CAP FOR AUTOMOBILE-RADIATORS.

58,294.

Specification for Design.

Patented July 5, 1921.

Application filed March 26, 1921. Serial No. 455,990. Term of patent 7 years.

To all whom it may concern:

Be it known that I, ALLAN L. McGREGOR, a citizen of the United States, residing at Chicago, in the county of Cook and State of Illinois, have invented a new, original, and ornamental Design for a Cap for Automobile-Radiators, of which the following is a specification, reference being had to the accompanying drawing, forming a part thereof.

Figure 1 is a view in front elevation of the cap, and

Fig. 2 is a perspective view of the cap.

I claim:

The ornamental design for a cap for automobile radiators, as shown.

ALLAN L. McGREGOR.

Witnesses:

SARAH E. HARVEY,
LURLINE BULLWINKEL.
